UNITED STATES PATENT OFFICE.

MELVIN H. SMITH, OF GALIEN, MICHIGAN.

COMBINATION-LOCK.

SPECIFICATION forming part of Letters Patent No. 596,185, dated December 28, 1897.

Application filed March 27, 1897. Serial No. 629,487. (No model.)

To all whom it may concern:

Be it known that I, MELVIN H. SMITH, a citizen of the United States, residing at Galien, in the county of Berrien and State of Michigan, have invented certain new and useful Improvements in Combination-Locks; and I do hereby declare the following to be a full, clear, and exact description of the invention, such as will enable others skilled in the art to which

10 it appertains to make and use the same.

My invention relates to a novel construction in a combination-lock, the object being to provide a cheap and simple device of this character in which a large number of combinations 15 are possible and which will permit changing of the combination at any time; and it consists in the features of construction and combinations of parts hereinafter fully described and claimed.

20 In the accompanying drawings, illustrating my invention, Figure 1 is a plan view of a combination-lock constructed in accordance with my invention with the cover removed. Fig. 2 is a longitudinal section of the same on 25 the line 2 2 of Fig. 1. Fig. 3 is a transverse section on the line 3 3 of Fig. 1. Fig. 4 is a detail sectional view of one of the keys.

Referring now to said drawings, A indicates a box or casing containing a frame B, consisting 30 of two longitudinal plates 1 and two cross-pieces 2. Said plates 1 are provided adjacent their upper edges with recesses 3, in which keys 4 are adapted to be slidably mounted. Said keys 4 consist of plates 5, provided with 35 slots 6, which are adapted to be partially covered and thus reduced by means of plates 7, pivoted to said plates 5 on each side of said slots 6. Said plates 7 are of greater extent on one side of said pivots than on the other 40 side thereof, so that when the shorter side lies between said slot 6 and said pivot the inner edge of said plate 7 is flush with the end of the slot, and when turned one hundred and eighty degrees the longer end thereof will project 45 over said slot, and thus reduce the same. Said keys 4 are further provided with pins 8, which are adapted to abut against the sides of the box A to limit the movement of the keys in that direction and also to serve as bearings 50 for springs 9, interposed between the same and the adjacent outer faces of the plates 1, said springs being trained around said keys.

Said box A is provided with recesses 10 in its sides, through which the ends of the keys 4 beyond the pins 8 are adapted to project. 55 Said slots 10 in one side of said box A are situated in alinement with alternate recesses 3 of the plates 1, while the recesses 10 in the other side of said box are situated in alinement with the remaining recesses 3, so that 60 one half of the keys project from one side of the box and the remainder from the opposite side. By means of the pins 8 and springs 9 said keys 4 are so adjusted in position in said box or casing A as to be located midway between the plates 1, so as to limit the passage of the bolt 11 therethrough and through slots 12 in the ends of said box or casing and in the cross-pieces 2. Said bolt 11 is adapted to move longitudinally, the movement thereof 65 being limited by means of a pin 13, adapted to abut against one of said cross-pieces 2 when said bolt has reached the rearward limit of its movement and against the adjacent end of the box when said bolt has reached the forward limit of its movement. A pin 14 is also provided in the opposite end portion of said bolt 11, between which and the adjacent plate 2 a spring 15 is interposed, which serves to hold said bolt 11 normally at the rearward 70 limit of its movement. Said bolt 11 is provided with a series of corresponding notches on both sides and between said pins 13 and 14, so as to form a series of rearwardly-facing shoulders 16, which are adapted to be engaged 75 by such of the plates 7 on said keys 4 as partially cover the slots 6 therein. The widest portion of said bolt 11 is adapted to fit and move freely through said slots 6 when the plates 7 nearest the projecting ends of said 80 keys are turned so as to partially cover said slots 6 and the opposite plates 7 are turned so that the edges thereof are flush with the adjacent ends of said slots 6, while if the position of said plates 7 on several of said keys 85 4 is reversed the plates 7 at the inner ends of said keys will project into the notches, so as to be thrown into engagement with said shoulders 16 when said bolt 11 is moved to the forward limit of its movement, as shown in Fig. 95 4. In Fig. 1 the plates 7 on the keys a, b, c, d, and e are turned so as to permit the free movement of the bolt 11 between the same, while the plates 7 on the keys f, g, and h are 100

turned so that the endmost plates project into the notches. Obviously by moving said bolt 11 to the forward limit of its movement, as indicated by the arrow, the inclined edges 5 formed by the notches would engage said endmost plates 7, thus drawing the keys *f*, *g*, and *h* to the inner limits of their movement against the action of said springs 9 until the next succeeding shoulders 16 are passed, when said 10 springs 9 would throw the said plates 7 into engagement with said shoulders 16. To cause said bolt to spring back to the rearward limit of its movement, it will be obvious that the keys *f*, *g*, and *h* must be pressed inwardly to 15 the inward limit of their movement—that is, until their inner ends abut against the inner face of the opposite side of the box—thus throwing the endmost plates 7 out of the path of said shoulders 16. It will also be obvious 20 that all of said keys *f*, *g*, and *h* must be pressed simultaneously in order to release said bolt and that if all of said keys *f*, *g*, and *h* and any one or more of the remaining keys be 25 pressed simultaneously said bolt 11 cannot be released, for the reason that by pressing one of the keys not included in the combination the plate 7 thereon nearest the projecting end of the key will be thrown into the path of said shoulders 16, and thus prevent the movement 30 of the bolt.

In order to change the combination, the cover 17 must be removed, the keys 4 taken out, and the position of the plates 7 on those desired to be changed reversed. The keys 35 and cover are then replaced.

I claim as my invention—

1. In a device of the kind specified, the combination with a plurality of keys slidably mounted in a box or casing and provided with

slots, and plates pivotally mounted on said 40 keys and adapted to partially cover said slots, of a bolt adapted to pass through said slots and provided with shoulders adapted to be engaged by said plates when said bolt is at the forward limit of its movement, substantially as described. 45

2. In a device of the kind specified, the combination with a plurality of keys slidably mounted in a box or casing and provided with slots, and plates pivotally mounted on said 50 keys and adapted to partially cover said slots, of a bolt adapted to pass through said slots and provided with shoulders adapted to be engaged by said plates when said bolt is at the forward limit of its movement, means for 55 throwing said plates out of engagement with said shoulders, and a spring for causing said bolt to spring back to the rearward limit of its movement, substantially as described.

3. In a device of the kind specified, the combination with a bolt provided with a series of shoulders, of keys provided with slots adapted to receive said bolt, and with plates pivotally mounted thereon and adapted to be turned so that their inner edges are flush with or project over the adjacent ends of said slots, whereby said projecting plates on the inner ends of said keys are thrown into the path of said shoulders to engage said bolt and hold the same at the forward limit of its movement, 60 substantially as described. 65

In testimony whereof I affix my signature in presence of two witnesses.

MELVIN H. SMITH.
